UNITED STATES PATENT OFFICE.

GEORGE SWIFT, OF OAKDALE, MASSACHUSETTS.

PICKER-STICK BUNTER.

SPECIFICATION forming part of Letters Patent No. 727,859, dated May 12, 1903.

Application filed October 22, 1902. Serial No. 128,279. (No model.)

To all whom it may concern:

Be it known that I, GEORGE SWIFT, a citizen of the United States, residing at Oakdale, in the county of Worcester and State of Massachusetts, have invented a new and useful Picker-Stick Bunter, of which the following is a specification.

This invention relates to a shuttle-motion attachment for looms.

10 The especial object of this invention is to provide a strong, simple, and inexpensive stop or bunter for limiting the operating stroke of a picker-stick.

To these ends this invention consists of the 15 parts and combinations of parts, as hereinafter described, and more particularly pointed out in the claims at the end of this specification.

In the accompanying drawings, Figure 1 is 20 a front view of sufficient parts of a loom to illustrate the application of my invention thereto. Fig. 2 is an enlarged side view of the attachment, and Fig. 3 is a front view thereof.

25 In the ordinary loom picker-sticks are employed for throwing the shuttles from one side of the loom to the other. These picker-sticks are mounted to swing back and forth with the lathe. Each picker-stick is given 30 its inward or operating throw by means of a sweep-strap, and each picker-stick is returned to normal position by a spring. In practice some means are required to limit the operating stroke of a picker-stick. On most of the

35 modern looms the operating stroke of each picker-stick is limited by a stop or bunter carried by the lathe. The use of a stop or bunter mounted on the lathe is objectionable, as it adds a certain amount of weight to a moving

40 part, while the swinging motion of the lathe itself increases the jar or shock to which the bunter is subjected, so that the same is more liable to be jarred out of position. In the older type of looms the operating stroke of

45 the picker-stick is usually limited by a strap or sling, which in some instances is secured to the loom-frame. The use of a leather strap or sling for limiting the operating stroke of a picker-stick is objectionable, as a strap when

50 employed in this location is speedily worn out and broken. To overcome these defects, it has been proposed to provide special stopping de-

vices which are mounted upon the loom-frame. The stopping devices of this character have, however, been so complicated that they have 55 not as yet come into general use.

The especial object of my present invention is to provide a stationary picker-stick bunter of that class adapted to be secured to the loom-frame of such simple, rigid, and efficient construction that it may be applied to nearly all classes of looms and which will wear for long periods.

To these ends a picker-stick stop or bunter constructed according to this invention comprises a bracket and a support adjustably secured to the bracket, which support carries a rubber cushioning-block which is bound in place by a leather girdle or strap.

When the parts of a picker-stick bunter 70 constructed according to this invention are properly adjusted and secured together, they occupy a stationary or fixed position and are not subject to the wear of moving parts.

Referring to the accompanying drawings, A designates a lathe-frame carried by swinging arms B, journaled on shaft S. Carried by and swinging with the lathe is a picker-stick P, which is swung in on its operative stroke by a sweep-strap L and is drawn back 80 by a return-spring R. F designates a portion of the loom-frame. These parts may be of any of the ordinary or approved constructions and need not be herein described at length.

85 A stop or bunter constructed according to this invention comprises a bracket or support 10, which may be secured to the loom side by bolt 11. Adjustably mounted on the bracket 10 is a support or angle-piece 12. The bracket 10 and piece 12 have intermeshing ribs, and the piece 12 is fastened in its adjusted position by a bolt 13, having a nut 14 threaded thereon. At its inner end the piece 12 is provided with an inclined face 15, and resting 90 against the inclined face 15, so as to be supported by a small lip 16, projecting out from the face 15, is a rubber block 17. The rubber block 17 is held down by a stop 18, fastened by a screw 19, and is bound onto the 95 inclined face 15 by a leather girdle or belt 20.

The leather girdle or belt 20 provides a proper wearing-face for the bunter, and in practice a bunter of this construction can be run for

long periods of time before the leather girdle 20 needs to be replaced. The practical advantages of a picker-stick bunter as thus constructed are that the bunter is less liable to 5 be knocked out of position than when secured on the lathe or other moving part, that the old forms of leather slings or straps are not required, and that no moving parts, springs, sliding rods, or other pieces are employed 10 which are liable to crystallize or be broken.

I am aware that changes may be made in 15 practicing my invention by those who are skilled in the art without departing from the scope thereof as expressed in the claims. I 20 do not wish, therefore, to be limited to the construction I have herein shown and described; but

What I do claim, and desire to secure by Letters Patent of the United States, is—

20 1. In a loom, the combination of the frame, and a picker-stick bunter secured to the frame to occupy a fixed or stationary position, said bunter comprising a supporting-face, a rubber cushion, and a leather girdle holding the 25 cushion in place upon the supporting-face, and furnishing a leather face against which the picker-stick strikes.

2. In a loom, the combination of the frame, and a picker-stick bunter secured to the frame

to occupy a stationary or fixed position, said 30 bunter comprising a bracket adapted to be bolted to the frame, a support adjustably mounted on the bracket and having an inclined face, a rubber striking-cushion, and a leather girdle binding the rubber cushion in 35 place upon the inclined supporting-face, and providing a leather surface against which the picker-stick strikes.

3. As an article of manufacture, a picker- 40 stick bunter adapted to be secured to the loom-frame to occupy a fixed or stationary position, comprising a bracket to be bolted to the frame, a substantially L-shaped support adjustable on said bracket, said parts having intermeshing ribs, and the support having an 45 inclined face with a ledge or projection along the lower edge thereof, a rubber cushion, and a girdle of leather binding the leather cushion in place upon the supporting-face, and providing a leather surface against which the 50 picker-stick strikes.

In testimony whereof I have hereunto set my hand in the presence of two subscribing witnesses.

GEORGE SWIFT.
